UNITED STATES PATENT OFFICE.

TALBOT G. MARTIN, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

MEASURED-SERVICE TELEPHONE SYSTEM.

1,169,102.

Specification of Letters Patent.

Patented Jan. 18, 1916.

Application filed January 17, 1907. Serial No. 352,693.

To all whom it may concern:

Be it known that I, TALBOT G. MARTIN, a citizen of the United States of America, and resident of Chicago, Cook county, Illinois, have invented a certain new and useful Improvement in Measured-Service Telephone Systems, of which the following is a specification.

My invention relates to telephone systems in general, but more particularly to automatic or semi-automatic telephone exchange systems, and especially to common battery systems.

Broadly considered, my invention contemplates a measured service telephone system in which there are call-registering devices allotted to the different subscribers' stations and controlled by the called subscribers. With such arrangement, a calling subscriber obtains connection in any suitable manner with the line of the called subscriber, but the call is not registered until the called subscriber answers—that is to say, it is the act of the called subscriber in answering which actuates the meter or call-registering device of the calling subscriber for the purpose of registering a successful call.

More specifically considered, my invention contemplates a call-registering device or meter which is located at the exchange or central station, or at the terminal of the subscriber's line, and which is always controlled or actuated by the called subscribers.

My invention also contemplates a system in which automatic means are provided and controlled by the calling subscribers for trunking through the exchange and into connection with the lines of the called subscribers, and in which call-registering devices or meters are allotted to the different subscribers' lines and associated with the first-selectors or other suitable individual switches at which the different subscribers' lines terminate.

Furthermore, my invention contemplates a system in which call-registering devices are allotted to the different subscribers' lines and provided with coils or relay windings through which battery current is fed to the calling subscribers' lines for talking purposes.

My invention also contemplates certain other features of novelty and combinations and details of construction, as will herein-
55 after more fully appear.

In the accompanying drawings, Figures 1 and 2 taken together are a diagram of an established connection between a calling and a called substation. The calling substation is shown at A and the called substation at 60 A'. For the purpose of explaining my invention, the substations may be considered as being at the same or different exchanges; but in this case the substation A, the line #500 to which is allotted the switch C, 65 shown in Fig. 1, and the substation A', the line #220 to which is allotted the switch C', together with the connector switch D, are considered as belonging to the same exchange. For operating the central office 70 switching apparatus a central current source B is provided having its positive terminal preferably grounded. Between the said substations there is shown the connecting central office switching apparatus comprising 75 switches characterized by many well-known features. The selector switches C and C' are a modification of the selector switch disclosed in United States Letters Patent No. 815,321, granted March 13, 1906, to Keith, 80 Erickson and Erickson. Fig. 3 is a diagram of the first-selector and the meter.

The substations A and A', like substations usually employed in connection with switches of the aforesaid type, are each provided with a dial which the subscribers operate for sending impulses over the line to operate the switches at the central office. They are provided, in addition, with the usual telephone switch-hooks through the 90 medium of which the substation ground circuit, the release circuit, and the primary, secondary and ringing circuits are suitably submitted to the control of the subscribers.

The substation A may be of any suitable 95 or approved type. The one in connection with which I have elected to illustrate my invention comprises a receiver 2, and a switch-hook 3 for controlling the substation circuits, which controlling operations are accomplished through the medium of any suitable means, such as the cam arms 4, 5 and 6. As the switch-hook is lowered, the cam arm 4 momentarily presses the release springs 7, 8 and 9 into engagement, whereby the substation line conductors may be grounded simultaneously. When the switch-hook is down, the cam arm 5 maintains a contact between the springs 10 and 11, thereby bridging the ringer 12 in series with the condenser 110

13 across the line. The substation ground circuit is normally broken between the ground springs 14 and 15 by the cam arm 6; but when said springs are together, 5 ground is then provided to the ground post 16 and to the release spring 7, as is usually the case in telephones of this type. The said substation comprises the usual transmitter 17 and induction-coil 18, the latter having 10 the primary winding 19 and secondary winding 20. Said substation is also provided with the usual vertical and rotary impulse springs 21 and 22, and is, of course, provided with a dial (not shown) secured to the shaft, and with the locking dog 23. Furthermore, there is a locking cam 24 that locks the dog 23, while the receiver is on the switch-hook, to prevent a rotation of the dial. For operating the impulse springs 21 15 and 22 the substation is provided with an impulse wheel 25 that is secured to the shaft 26, which impulse wheel carries on its periphery the so-called vertical impulse teeth 27^a and one rotary impulse tooth 28^a. The 20 said impulse teeth are so arranged that when the dial is drawn down the impulse springs 21 and 22 are not carried into contact with the ground post 16; but as the dial returns, first the vertical teeth engage the vertical 25 impulse spring 21, and after they have completed their work the rotary impulse tooth operates the rotary impulse spring 22. In this operation the subscriber's vertical line conductor 27 is first given a number of 30 ground impulses, and then the rotary line conductor 28 is given one ground impulse. It will be noticed that as long as the dial is 35 out of normal position the construction is such that the dog 23 permits the primary circuit springs 29 and 30 to separate, thus preventing the impulses that are delivered to either line conductor from passing to the other. Means whereby a subscriber may 40 signal a called subscriber comprises the push-button 31 which, when pressed, carries the spring 32 out of engagement with the contact point 33 and into engagement with the contact point 34, whereby the vertical line conductor 27 is grounded. 45 The selector switch C is of the general type of selector switch disclosed in United States Letters Patent No. 815,321, above referred to, except that the so-called side switch is omitted and the circuits modified 50 accordingly. Among other details the selector switch C, in connection with which my meter mechanism is shown, comprises the usual vertical and rotary line relays 35 and 36 which in turn control the vertical 55 and rotary magnets 37 and 38, respectively. By means of the finger arm 39, the rotary magnet in turn operates the armature 40 of the private magnet 41, which latter maintains its own energizing circuit under conditions, as will be explained. The release of 60

the said switch is brought about by the usual release magnet 42, which latter is controlled by the vertical and rotary line relays 35 and 36 conjointly. After the switch has operated and established connection with a trunk line leading to a second switch, the release magnet 42 is controlled from the second switch through the release relay 43. Furthermore, when the connection is established with the next succeeding switch, the line 70 switching relay 44 operates to disengage the line conductors 27 and 28 from the vertical and rotary line relays 35 and 36, and to extend the said line conductors to the seized trunk line through the wipers 45 and 46 75 which, with the private wiper 47, are carried upon the switch-shaft 48. Under the control of the shaft cam 49 are the cam springs 50, 51 and 52 which, when the shaft is in a rotated position, maintain a guarding potential at the connector bank over the private normal conductor 53, through the springs 51 and 52, for protecting the line allotted to the switch. Furthermore, the switch-shaft 48 is provided with a normal 80 arm 54 which, when the shaft is in an operated position, permits the springs 55 and 56 to engage, whereby an energizing circuit is closed through the off-normal lamp 57 when the cam springs 50 and 51 are in engagement. 85 This occurs when the switch-shaft is in a vertically operated position only. Now when the shaft receives a rotary impulse, the cam 49 passes from the control of the said cam springs, whereby the spring 51 passes out of engagement with the spring 52. 90 95 The relays comprised in my meter or registering arrangement are the relays 58 and 59 which are connected in series with the windings 60 and 61, respectively, of the differential relay 62. The said relays 58 and 59 are so arranged that when both relays energize simultaneously, the springs 63 and 64 then engage; but when either relay operates alone the springs 63 and 64 do not engage. The relay 62 operatively energizes when the two windings 60 and 61 are connected in series; but when the windings are 100 in multiple the said relay does not operatively energize, since the said windings are differentially arranged; and when current passes through the windings in multiple, as stated, the windings 60 and 61 then oppose each other. The meter magnet 65 is provided for operating the meter register 66, which can be of any suitable construction, as the exact character of the numerals, wheels or registering mechanism is unimportant. The condensers 67 and 68 divide 110 the circuit through the switch into two sections and serve to increase the efficiency of the talking circuit. 120 125

The connector switch D may also be of any suitable or approved type, for instance 130

of the general type described in United States Letters Patent No. 815,176. The mechanical details of the selector and connector, as is well known, are very much the same, although there is a difference in the circuits. For instance, the connector switch-shaft which is not shown carries, like that of the selector, the line wipers 69 and 70 and the private wiper 71. The connector switch is also controlled by the calling subscriber through the medium of the vertical and rotary line relays 72 and 73. The vertical line relay 72 directly controls the vertical magnet 74 and also the rotary magnet 75. The office of the vertical magnet 74 is to give the shaft and shaft wipers a vertical motion, and the rotary magnet 75 imparts to the shaft and shaft wipers a rotary or circular motion. The rotary line relay 73 controls the private magnet 76 which, under certain conditions, in turn controls the vertical and rotary magnets 74 and 75, the release magnet 77, and also the side switch wipers 78, 79, 80 and 81. The said side switch, like the side switch of the selector, has a normal or first position, a second position and a third position. The release magnet 77 is also controlled by the vertical and rotary line relays 72 and 73 conjointly. By the use of the condensers 82 and 83 the connector divides the circuit through it into two sections to separate the calling and called subscribers' talking current feeding circuits, for well known reasons. The connector is provided with a differentially wound relay 84 which is composed of the windings 85 and 86. The function of this relay is to enable the calling subscriber to release and to energize the ringer relay 88 for signaling. Said relay provides the means by which the ringer generator E is bridged across the terminals of the called line to signal the called subscriber. The back-bridge relay 87, comprising the windings 89 and 90, provides the calling subscriber with talking battery current when the primary circuit of the called substation is bridged across the line. The central station is equipped with the busy signaling apparatus F of any suitable design, as, for example, the one comprising an interrupter 91 in series with the primary winding 92 of the induction-coil 93, whereby a busy signaling current is induced in the secondary winding 94 of the said induction-coil. The secondary winding 94 is connected with the side switch wiper 79, through the normal springs 95 and 96, when the side switch is in first position and when the connector switch-shaft is raised.

The operation of my meter device may be more clearly understood by following its action when a subscriber calls another subscriber and the called subscriber answers.

Suppose, for example, that the subscriber

at substation A calls and signals the subscriber at substation A' on line #220, and the latter subscriber then answers. The first digit being 2 the subscriber at substation A turns his dial for the first digit 2, thereby 70 first grounding the vertical line conductor 27 twice and the rotary line conductor 28 once upon the return motion of the dial. Grounding the vertical line conductor 27 by the forward motion of the dial energizes the 75 vertical line relay 35 of the selector C, which in turn operates to close an energizing circuit through the vertical magnet 37. The vertical line conductor 27 being grounded twice the vertical magnet 37 energizes twice 80 to raise the selector shaft 48 and wipers 45, 46 and 47 two steps. The said wipers are carried opposite a level in which are the contact points that constitute the terminal 85 of the trunk line leading to the connector switch D. Following the vertical impulse the rotary impulse operates the rotary line relay 36 which, upon energization, closes a circuit; then the rotary magnet 38 rotates the shaft wipers 45, 46 and 47 onto the first 90 set of contacts, and the rotary magnet armature 97, by means of the arm 39, operates the private magnet armature 40, whereby the springs 98 and 99 engage and close an energizing circuit through the said private 95 magnet, if the first trunk line is busy. This private magnet circuit extends from the grounded private wiper 47 through the release relay 43, private magnet springs 98 and 99, private magnet 41, through the release magnet springs 100 and 101 to the battery lead 102, thence through battery B to ground G. The private magnet 41, upon energizing, maintains an energizing circuit 100 through the rotary magnet 38 extending from ground G² through the private magnet springs 103 and 104 to the rotary interrupter springs 105, thence through the rotary magnet 38 to the battery lead 102, 105 thence through battery B to ground G. The rotary magnet, by continuing to rotate the wipers, breaks the energizing circuit of the private magnet 41 as soon as an idle trunk line is found. If, however, the first nine 110 trunks are busy, the shaft wipers will be rotated onto the tenth set of contacts or tenth terminal, the trunk line allotted to which terminal, it will be assumed, being idle and upon which the wipers come to rest. 115 When the private magnet 41 deenergizes a guarding potential is established at the engaged private wiper contact for protecting the seized trunk lines. This guarding potential extends from ground G² through the private magnet springs 103 and 98, through 120 the winding of the back-release relay 43 to the private wiper 47, which wiper engages the conductor 106. The guarding potential for protecting the calling line extends from 125 ground G³ through the cam springs 51 and 130

52, private normal conductor 53 to the connector bank. The line switching relay 44 operates as soon as the private wiper 47 engages an idle bank contact and the private magnet 41 deenergizes. The energizing circuit through the said relay extends from ground G³ through the cam springs 51 and 52, through the winding of the line switching relay 44 to the interrupter springs 105, 10 thence through the rotary magnet 38 to the battery lead 102, thence through battery B to ground G. It will be observed that the rotary magnet is included in this circuit; but since the relay 44 is of twenty-three hundred ohms resistance, and the rotary magnet of sixty ohms resistance, there is not sufficient current passing to operatively energize the said rotary magnet.

The line switching relay, as previously explained, operates to disconnect the subscriber's line conductors 27 and 28 from the vertical and rotary line relays 35 and 36, respectively, and to extend the said conductors to the shaft wipers 45 and 46 and to the trunk conductors 107 and 108 which lead to the connector D. The grounding of the line conductors 27 and 28 for the last two digits affects the connector by operating the vertical and rotary line relays 72 and 73. 25 When the said vertical line conductor 27 is grounded the vertical line relay 72 is energized by a flow of current from the substation ground G', vertical impulse spring 21 to the vertical line conductor 27, line switching relay springs 109 and 110, relay 58, winding 60 of the differential relay 62, shaft wiper 45, conductor 107, through the connector vertical line relay 72, winding 85 of the differential relay 84 to the battery lead 102, thence through battery B to ground G. 30 The relay 58 and the windings 60 and 85 of the relays 62 and 84, respectively, being included in this circuit, the said relays energize, but their operation at this particular time is without effect. Each time that the vertical line relay 72 operates for the second digit, the vertical magnet operatively energizes to carry the shaft wipers 69, 70 and 71 in a vertical direction one step at a time 35 until the said wipers are carried two steps and thus brought opposite a level in which are located the terminals of the line #220. When the rotary line conductor 28 is grounded the connector rotary line relay 73 becomes energized through a circuit extending from the substation ground G' through the rotary impulse spring 22, rotary line conductor 28, line switching relay springs 111 and 112, relay 59, winding 61 of the 40 relay 62, shaft wiper 46, conductor 108, rotary line relay 73, winding 86 of the differential relay 84, through the springs 113 and 114 to the battery lead 102, thence through battery B to ground G. The windings of 45 the relays 59, 62 and 84 being included in

this circuit as in the vertical line relay circuit, the said relays energize, but with no effect. The rotary line relay 73, upon energizing, operates to close an energizing circuit through the private magnet 76, which latter in turn operates to release the side switch from first to second position. For the last digit the subscriber operates the dial, as previously described, grounding the vertical line conductor 27 ten times and the rotary line conductor 28 once. The connector vertical and rotary line relays 72 and 73 are operated over previously traced circuits. However, when the vertical line relay operates, a circuit is closed through the rotary magnet 75 instead of through the vertical magnet 74. Each time that the rotary magnet is energized the shaft wipers 69, 70 and 71 are rotated one step at a time until the said wipers are carried into engagement with the normal conductors 115, 116 and 117, the first two of which conductors lead to the line terminals of the desired substation. The rotary line relay 73, upon energizing, completes an energizing circuit through the private magnet, which latter now operates with one of two results, viz, the release of the side switch from second to third position, or the so-called busy release of the connector. It will be assumed that the former result occurs and that the side switch passes to third position, whereby the side switch wipers 78 and 79 are placed in connection with the shaft wipers 69 and 70, respectively. Furthermore, when the side switch passes to third position a guarding potential is established for protecting the called line. The said guarding potential also closes an energizing circuit through the line switching relay 118 of the selector C', which relay 105 operates to close the springs 119 and 120 and 121 and 122 in contact, whereby the normal conductors 115 and 116 are extended to the line conductors 123 and 124 which lead to substation A'. The circuit through 110 the line switching relay 118 extends from ground G⁵ through the side switch wiper 80, to the connector shaft wiper 71 (Fig. 1), to the conductor 117 (Fig. 2), thence through the winding of the line switching relay 118, 115 interrupter springs of the rotary magnet, winding of the rotary magnet to the battery lead 102, thence through battery B to ground G.

In order to signal, the subscriber at substation A presses the signaling button 31, whereby the vertical line conductor 27 is grounded, and the connector vertical line relay 72 and the differential relay 84 become energized as before. It will be remembered that the side switch has passed from second to third position and the side switch wiper 81 is in engagement with the contact point 130, thereby placing the vertical line relay 72 in control of the ringer 130

relay 88 in the same manner in which the rotary magnet 75 came under the control of the vertical line relay when the side switch passed from first to second position. Therefore, when the vertical line relay presses the springs 126 and 127 into contact the ringer relay 88 is energized by a flow of current from ground G⁴ through the springs 126 and 127, private magnet springs 128 and 129, side switch wiper 81, contact point 130, ringer relay 88, springs 131 and 132, (bearing in mind that the differential relay 84 is energized), to the battery lead 102, thence through battery B and to ground G. The ringer relay, upon energizing, shifts the spring 133 from contact with the spring 134 into engagement with the spring 135, and the spring 136 is shifted into engagement with the spring 137. This results in bridging across the called subscriber's line the terminals of the ringer generator E. A signaling current is therefore sent from the generator E to the ringer relay springs 137 and 136, side switch wiper 78, contact point 138, shaft wiper 69, normal conductor 115, line switching relay springs 119 and 120, vertical line conductor 123, condenser 139, ringer 140, springs 141 and 142 to the rotary line conductor 124, line switching relay springs 122 and 121, rotary normal conductor 116, shaft wiper 70, contact point 143, side switch wiper 79, ringer relay springs 133 and 135 back to the generator E. As soon as the calling subscriber ceases to press the signaling button 31 the ringer relay 88 becomes deenergized and the springs 133 and 136 resume their normal position. The subscriber at substation #220, in response to the signal, removes the receiver 144 from the switch-hook 145, which allows the springs 146 and 147 to engage, and the springs 141 and 142 to disengage, thereby removing the ringer 140 from across his line. The engagement of the springs 146 and 147 closes a series energizing circuit through both windings of the relay 87 at the connector D, this circuit extending from ground G⁵ to the contact point 148, side switch wiper 80, winding 90 of the relay 87, through the ringer springs 134 and 133, side switch wiper 79, contact point 143, shaft wiper 70, rotary normal conductor 116, line switching relay springs 121 and 122, rotary line conductor 124, primary winding 149, transmitter 150, through the signaling device of the called substation, through the springs 146 and 147, vertical line conductor 123, line switching springs 120 and 119, conductor 115, shaft wiper 69, contact point 138, wiper 78, through the winding 89 of the relay 87, springs 151 and 132 to the battery lead 102, thence through battery B and to ground G. The relay 87, upon energization, operates to shift the spring 113 from the spring 114 (which lat- ter is connected to the battery lead 102) to the spring 152, which latter is in turn connected with ground. The reversal of the polarity of the spring 113 sets up a circuit which provides the calling substation with battery current for talking purposes. This circuit may be traced from ground G⁵ to the contact point 148, side switch wiper 80, through the springs 152 and 113, winding 86 of the differential relay 84, rotary line relay 73, conductor 108, shaft wiper 46, winding 61 of the differential relay 62, relay 59, line switching relay springs 112 and 111, rotary line conductor 28, primary winding 19, transmitter 17, springs 29 and 30, vertical line conductor 27, line switching relay springs 109 and 110, relay 58, winding 60 of the differential relay 62, shaft wiper 45, conductor 107, vertical line relay 72, winding 85 of the differential relay 84 to the battery lead 102, thence through battery B and to ground G. Since the windings of the relays 58, 59 and 62 of the meter mechanism are included in this circuit, the said relays energize simultaneously, the relays 58 and 59 closing the springs 63 and 64 in contact, and the relay 62 closing the springs 153 and 154 in contact, whereby an energizing circuit is established through the meter magnet 65 from ground G⁶, through the springs 63 and 64, springs 153 and 154, magnet 65, and to the battery lead 102, thence through battery B to ground G. The meter magnet, upon energizing, attracts its armature 157, whereby the pawl 158 engages the teeth of the meter wheel 159, rotating said wheel one step, which is registered on the meter 66. Furthermore, when the armature 157 operates, the springs 155 and 156 engage, thereby closing a second or locking circuit through the meter magnet 65. This locking circuit extends from ground G⁵ through the cam springs 51 and 52, meter magnet springs 155 and 156, through the said meter magnet to the battery lead 102, thence through battery B and to ground G. The function of this second circuit is to maintain the meter magnet in an inoperative condition until the calling subscriber restores his receiver to the switch-hook, which results in the release of the switches employed, and the restoration of the cam springs 50, 51 and 52 to normal position—that is, the spring 51 disengages from the spring 52 and closes in contact with the spring 50, thus destroying the locking circuit of the meter magnet. If this locking circuit were not provided, then if for any reason the called subscriber should restore his receiver to the switch-hook and again remove the same before the calling subscriber releases, battery current for talking purposes is cut off from both the calling and called substations and again supplied, which would again energize the relays 58, 130

59 and 62 simultaneously, thus again energizing the meter magnet 65 which would operate a second time. To prevent the meter from thus registering twice for one call the locking circuit is provided. The release of the switching apparatus is brought about when the calling subscriber restores the receiver 2 to the switch-hook 3, thereby pressing the release springs 7, 8 and 9 into engagement for a moment. The contact of the said release springs grounds the vertical and rotary line conductors 27 and 28 simultaneously from ground G' to the release spring 7, thence through the springs 8 and 9 to the vertical and rotary line conductors. The grounding of the rotary line conductor 28 produces a short-circuit of the rotary relay 73 in series with the winding 86 of the differential relay 84, said circuit extending from ground G⁵ at the connector to the contact point 148, side switch wiper 80, springs 152 and 113, winding 86 of the differential relay 84, rotary line relay 73 to the shaft wiper 46, winding 61, relay 59, line switching relay springs 112 and 111 to the rotary line conductor 28, release springs 8 and 7 to the substation ground G'. Therefore, since the winding 85 of the differential relay 84 alone carries current, the said relay becomes energized and attracts its armature, which shifts the spring 132 out of contact with the spring 151 into contact with the spring 131. The disengagement of the springs 151 and 132 destroys the energizing circuit through the relay 87, and the spring 113 passes out of engagement with the spring 152 and into engagement with the spring 114, which removes the said short-circuit of the rotary relay 73 and winding 86, and establishes an energizing circuit instead extending from the substation ground G' through the release springs 7 and 8 to the rotary line conductor 28, then to the rotary line relay 73, as previously traced, winding 86 of the differential relay 85, through the springs 113 and 114 to battery lead 102, thence through battery B to ground G. The rotary relay 73 now operates and the springs 160 and 161 come into contact, whereby an energizing circuit is established through the release magnet 77 of the connector D and the release relay 43 of the selector C. However, the current now in passing, as above stated, through the winding 86 aids the winding 85 in maintaining the springs 131 and 132 in contact. The energizing circuit through the release relay 43 and release magnet 77 extends from ground G² at the selector C, private magnet springs 103 and 98, release relay 43, shaft wiper 47, trunk release springs 160 and 161, release magnet 77, springs 131 and 132 to battery lead 102, and through battery B to ground G. When the connector release magnet 77 is thus supplied with current it

energizes, and as a result the switch-shaft and side switch are restored to normal position, thus breaking the connection between the connector switch-shaft wipers 69, 70 and 71 and the normal conductors 115, 116 and 70 117.

The back-release relay 43 being in the same circuit with the release magnet energizes simultaneously with the latter and operates to close a circuit through the selector release 75 magnet 42 by pressing together the back-release springs 164 and 165. The circuit through the said release magnet 42 extends from ground through the release springs 164 and 165 to the release magnet 42, thence to 80 the battery lead 102, and through battery B to ground G. When the ground to the line conductors 27 and 28 is interrupted all the magnets involved in the release are de-energized and all the switches are fully re-85 stored. When the switch C is fully restored the cam spring 51 passes out of engagement with the spring 52, whereby the locking circuit through the meter magnet 65 becomes broken and the said magnet returns to normal position. If the called line #220 is busy at the time that the calling subscriber #500 attempts to establish connection, the connector D is released by the last impulse to the rotary line conductor 28, as follows: The 95 said impulse energizes the rotary line relay 73 of the connector D, which relay in turn energizes the private magnet 76, pressing the private springs 166 and 167 into contact after the private wiper 71 has been carried 100 onto the grounded private bank contact. Of course, it is understood that whenever a line is busy the connector private bank contacts connected with the private normal 117 are all connected to ground. Therefore, since 105 the connector side switch is in second position when the private springs 166 and 167 are brought into contact, an energizing circuit is established through the release mag-110 net 77 from the said grounded private bank contact to the private wiper 71, thence to the side switch wiper 80 (which is in second position) to the private magnet springs 167 and 166, to the release magnet 77, through the springs 131 and 132 to the battery lead 115 102, thence to the battery B and to ground G. The connector switch-shaft and side switch are thus released and connection is not estab-120 lished with the called line. Now, when the calling subscriber presses the signaling but-125 ton, the vertical line relay 72 becomes energized and operates to close a circuit through the vertical magnet 74. The vertical magnet operates to carry the switch-shaft vertically, whereby the off-normal springs 95 and 96 engage to permit the busy signaling current to pass to the calling subscriber in the usual way. Of course, when the subscriber hangs up his receiver after receiving the busy signal, he grounds the line relays 72 and 73 of 130

the connector D, as already explained, producing the release of the switching apparatus as formerly. Now when the line conductors 27 and 28 are grounded and current passes through the meter line relays 58 and 59 and through the windings 60 and 61 of the differential relay 62, the said relays 58 and 59 energize, but the relay 62 does not energize and, therefore, the springs 153 and 154 do not engage, and, of course, since the meter magnet 65 does not become energized the meter does not register.

The relays used in my meter device may be wound to any suitable resistance, but good results have been obtained when the relays 58 and 59 are wound to a resistance of thirty ohms each, the windings of the relay 62 to a resistance of thirty ohms each, and the meter magnet to a resistance of one hundred ohms.

From the foregoing it will be seen that I provide call-registering devices which are operated by the called subscribers to register the successful calls. As illustrated, these call-registering devices or meters are located at the exchange or central station, but it is obvious that for the broader purposes of my invention they may be located at other points in the general system. Furthermore, it will be seen that these call-registering devices or meters are, after registering a call, always locked against further actuation, so that a disconnection and restoration are always necessary before a meter can be caused to register another call. In addition, these call-registering devices or meters are provided with coils or relay windings through which battery current is fed to the lines of the calling subscribers for talking purposes.

It will be understood, of course, that all of the different contacts or circuit-controlling devices can be adjusted or regulated in any suitable or known manner for the purpose of obtaining the desired results and the described mode of operation. It will also be understood, of course, that the first-selector C' has a bank of trunk line terminals for use when the subscriber's line to which it is allotted is used as a calling line. Should the subscriber at substation A' call the subscriber at substation A, the call-registering device or meter allotted to the first-selector C' will then be controlled or actuated by the subscriber at substation A, in order to register the successful call. Should the subscriber at substation A not answer, however, no registration of the call will be made, as previously explained.

What I claim as my invention is:

1. In a telephone exchange system, the combination of calling and called telephone lines, an automatic switch controlled over the calling line, means for registering the call as soon as the called subscriber answers, and means including said called telephone

line and a differentially wound relay individual to the calling line, but normally disconnected therefrom, for controlling the registering operations of said means.

2. In a telephone exchange system, the combination of connectors for making the final connections with called telephone lines, automatic means for trunking calling common battery telephone lines into connection with said connectors, call-registering devices allotted to the different telephone lines for registering the calls as soon as the called subscribers answer, and means including a differentially wound relay individual to the calling line, but normally disconnected therefrom, by which the called subscribers cause said devices to register the calls.

3. In a telephone exchange system, the combination of telephone lines, automatic means for connecting calling lines with called lines, including common battery connectors for finding the called lines, call-registering devices allotted to the different telephone lines, responsive to the called subscribers for the registration of calls, and means including the called telephone lines and a differentially wound relay individual to the calling line, but normally disconnected therefrom, for controlling the said devices and causing the same to register all successful calls.

4. In a telephone exchange system, the combination of a calling telephone line, a called telephone line, a common battery or centralized source of talking current, a call-registering device allotted to the calling line, a hook-switch for the called line, means responsive to the action of said hook-switch for admitting talking current to the calling line, means including a differentially wound relay responsive to said hook-switch for causing the said registering device to register the call, and means for locking said device against further operation while the two lines are connected.

5. In a telephone exchange system, the combination of calling and called telephone lines, a plurality of trunks, an individual automatic trunk-selecting switch for the calling telephone line, a relay temporarily energized to maintain the continuity of the talking connection between the two lines, a call-registering device allotted to the said individual switch and adapted for registering the call when the called subscriber answers, and means including line relays by which the called subscriber causes said device to register the call.

6. In a telephone exchange system, the combination of a calling telephone line, a call-registering device provided with a differentially-wound electromagnet, and a battery connected to supply current through the said differential windings to the calling line for talking purposes.

7. In a telephone exchange system, the combination of a calling telephone line, a call-registering device provided with a differentially-wound electromagnet, a battery connected to supply current through the said differential windings to the calling line for talking purposes, and a called telephone line over which the called subscriber controls the said device to register the call.
8. In a telephone exchange system, the combination of a calling telephone line, a called telephone line, a first-selector included between the two telephone lines, provided with a relay temporarily energized to maintain the continuity of the talking connection between the two lines, a toll device allotted to the calling telephone line, and means by which the called subscriber controls said device to assess toll for the successful call.
9. In a telephone exchange system, the combination of a calling telephone line, a called telephone line, means including a plurality of automatic switches for extending a connection from a calling to a called subscriber's line, a relay individual to a subscriber and temporarily energized to maintain talking connection between the two lines, and a call-registering device allotted to the calling telephone line, provided with a relay also temporarily energized during talking.
10. In a telephone exchange system, the combination of a calling telephone line, a called telephone line, means including a plurality of automatic switches for extending a connection from a calling to a called subscriber's line, a relay individual to a subscriber and temporarily energized to maintain talking connection between the two lines, a call-registering device allotted to the calling telephone line, provided with a relay also temporarily energized during talking, and means by which the called subscriber controls the said device to register the call.
11. In a telephone exchange system, the combination of a calling telephone line, a called telephone line, means including a plurality of automatic switches for extending a connection from a calling to a called subscriber's line, a relay individual to the calling telephone line and temporarily energized to maintain talking connection between the two lines, a toll device allotted to the calling line, and means for operating said toll device when the called subscriber answers.
12. In a telephone exchange system, the combination of a calling telephone line, a called telephone line, means including a plurality of automatic switches for extending a connection from a calling to a called subscriber's line, a relay temporarily energized to maintain the continuity of the talking
- connection between the two lines, a call-registering device allotted to the calling line, means by which the called subscriber operates said device to register the call, and means for locking the said device against further operation while the two lines are connected.
13. In a telephone exchange system, the combination of a calling telephone line, a called telephone line, a relay temporarily energized to maintain the continuity of the talking connection between the two lines, automatic means for trunking the calling line into connection with the called line, controlled by the calling subscriber, a trunk-release circuit, which circuit includes no portion of the talking circuit, a call-registering device allotted to the calling line, and means for disconnecting the two lines and restoring said call-registering device by the closure of said trunk-release circuit.
14. In a telephone exchange system, the combination of a temporarily established talking circuit, a call-registering device provided with a differentially-wound relay, and means for supplying talking current through the windings of said relay to the said talking circuit, the said call-registering device provided with a local operating circuit controlled by said relay.
15. In a telephone system, means including a differentially wound relay having one winding connected to each side of the talking circuit, by which the called subscriber controls the supply of talking current to the substation of the calling subscriber, and a call-registering device comprising a rotary element and means for actuating the same responsive to the flow of talking current to the calling subscriber.
16. In a telephone system, means by which the called subscriber controls the supply of talking current to the calling subscriber, a differentially wound relay individual to the calling subscriber and responsive to the flow of talking current, and a call-registering device controlled by said relay.
17. In a telephone exchange system, the combination of a calling telephone line, a call-registering device provided with a differentially-wound electromagnet, a battery connected to supply current through the said differential windings to the calling line for talking purposes, and means having one motion to select groups and another motion to connect with the called line in any group selected by the first motion of the same means, both motions controlled over said line from the substation thereof.
18. In a telephone exchange system, the combination of a calling telephone line, a called telephone line, a first-selector included between the two telephone lines, provided with a relay temporarily energized to maintain the continuity of the talking connection

- between the two lines, a toll device allotted to the calling telephone line, means by which the called subscriber controls said device to assess toll for the successful call, and means 5 having one motion to select groups and another motion to connect with the called line in any group selected by the first motion of the same means, both motions controlled over said line from the substation thereof.
- 10 19. In a telephone exchange system, the combination of a calling telephone line, a called telephone line, a relay temporarily energized to maintain talking connection between the two lines, a call-registering device 15 allotted to the calling telephone line, provided with a relay also temporarily energized during talking, and means having one motion to select groups and another motion to connect with the called line in any group 20 selected by the first motion of the same means, both motions controlled over said line from the substation thereof.
- 20 20. In a telephone exchange system, the combination of a calling telephone line, a 25 called telephone line, a relay individual to the calling telephone line and temporarily energized to maintain talking connection between the two lines, a toll device allotted to the calling line, means for operating said 30 toll device when the called subscriber answers, and means having one motion to select groups and another motion to connect with the called line in any group selected by the first motion of the same means, both 35 motions controlled over said line from the substation thereof.
21. In a telephone exchange system, the combination of a calling telephone line, a called telephone line, a call-registering device allotted to the calling line, means by 40 which the called subscriber operates said device to register the call, means for locking the said device against further operation while the two lines are connected, and means 45 having one motion to select groups and another motion to connect with the called line in any group selected by the first motion of the same means, both motions controlled over said line from the substation thereof.
- 50 22. In a telephone exchange system, the combination of a temporarily established talking circuit, a call-registering device provided with a differentially-wound relay, means for supplying talking current through 55 the windings of said relay to the said talking circuit, the said call-registering device provided with a local operating circuit controlled by said relay, and means having one motion to select groups and another motion 60 to connect with the called line in any group selected by the first motion of the same means, both motions controlled over said line from the substation thereof.
23. In a telephone system, a differentially 65 wound relay individual to the calling sub-
- scriber's line, responsive to the called subscriber, a call-registering device controlled by said relay, and means having one motion to select groups and another motion to connect with the called line in any group selected by the first motion of the same means, both motions controlled over said line from the substation thereof. 70
24. In a telephone system, a differentially wound relay individual to the calling subscriber, a call-registering device controlled by said relay, means by which the called subscriber energizes said relay when he answers, and means having one motion to select groups and another motion to connect with the called line in any group selected by the first motion of the same means, both motions controlled over said line from the substation thereof. 75
25. In a telephone system, means by which the called subscriber controls the supply of talking current to the calling subscriber, a differentially wound relay individual to the calling subscriber and responsive to the flow of talking current, a call-registering device controlled by said relay, and means having one motion to select groups and another motion to connect with the called line in any group selected by the first motion of the same means, both motions controlled over 80 said line from the substation thereof. 85
26. In a telephone system, means for extending a connection between a calling and a called subscriber's line, a service meter allotted to each calling line for registering such connections, a pair of line relays and a differential relay individual to the calling line, and means for energizing each of said line relays in series with a winding of said differential relay to control said meter. 90 100
27. In a telephone system, means for extending a connection between a calling and a called subscriber's line, a service meter allotted to each calling line for registering such connections, a pair of line relays and a differential relay individual to the calling line, and means for energizing each of said line relays in series with a winding of said differential relay and in series with the talking circuit to control said meter. 105 110
28. In a telephone system, means for extending a connection between a calling and a called subscriber's line, a service meter allotted to each calling line for registering such connections, a line relay, a differential relay, and means for energizing said relays in series in the control of said meter. 120
29. In a telephone system, means for extending a connection between a calling and a called subscriber's line, a service meter allotted to each calling line for registering such connections, a line relay, a differential relay, and means for energizing said relays in series over the talking circuit in the control of said meter. 125 130

30. In a telephone system, subscribers' lines, common battery means for supplying talking and signaling current to said lines, a pair of line relays and a double-wound relay individual to each line, means for including one of said relays and one winding of said double-wound relay in series in each side of the talking circuit, and a call-registering device controlled by said relays.
31. In a measured service telephone exchange system, a side switchless trunk se-

lector having vertical and rotary motion allotted to the calling line, and a call registering device associated with said selector controllable over the called line.

15
